UNITED STATES PATENT OFFICE.

MARK SHOELD, OF CHICAGO, ILLINOIS, ASSIGNOR TO ARMOUR FERTILIZER WORKS, OF CHICAGO, ILLINOIS, A CORPORATION OF NEW JERSEY.

ELECTRIC FURNACE.

1,274,796.

Specification of Letters Patent.

Patented Aug. 6, 1918.

Application filed January 28, 1918. Serial No. 214,055.

To all whom it may concern:

Be it known that I, MARK SHOELD, a subject of the King of Sweden, residing at Chicago, in the county of Cook and State of Illinois, have invented certain new and useful Improvements in Electric Furnaces, of which the following is a specification.

Improvements in electric chemical furnaces constitute the subject-matter of this invention, one of its prime and leading objects being to provide a furnace of this type, which is continuous in operation, and which provides a proper and even distribution of the gaseous ingredients throughout the body of solid material employed, both being at that time subjected to the required degree of heat, preferably produced electrically, and desirably by one or more electric-arcs disposed outside of the chamber in which the chemical action occurs, so as not to interfere with the feed of the material and to render the electrodes less subject to damage and injury. By employing electric-arcs for this purpose, the heat can be readily and desirably concentrated so as to act upon an intermediate zone or section only of the column of material passing through the conduit or chamber.

Another feature of the invention is to provide a structure of this general character in which a uniform intermixture of the solid material and gas can be obtained at the same time that it is practically uniformly subjected to the high degree of heat necessary to bring about the chemical reaction.

Preparatory heating of both ingredients, solid and gaseous, previous to their entry into the heat zone constitutes another important element of the invention, such heating being so brought about that the discharging materials after having traversed the heat chamber are more or less cooled, each having surrendered some, if not all of its heat to the other entering, and as yet untreated, element.

In the drawing, forming a part of this specification, I have illustrated several embodiments of the invention all of which are described in detail below.

50 In these drawings:

Figure 1 is a horizontal section through one form of the furnace;

Fig. 2 is a fragmentary vertical section on line 2-2 of Fig. 1;

55 Figs. 3 and 4 show in horizontal and verti-

cal section respectively a different style of the appliance; and

Fig. 5 depicts a furnace of this general character having an inclined instead of vertical or upright, conduit or passage for the material to be treated.

Referring first to the form of appliance of Figs. 1 and 2, it will be noticed that centrally it has a vertical, hollow body 10 of graphite or carbon or other suitable refractory material, providing a vertical conduit or passage 11 down which the body of solid pieces, such as briquets composed of finely-divided carbon, alumina, and a binder, descend by gravity in a slow but continuous stream. Near the lower portion of such passage or chamber the furnace is provided with one or more gas-inlet pipes 12 through which a suitable gas, such as nitrogen, or a nitrogen-containing gas, free from oxidizing elements, is introduced under pressure into the lower section of such body of briquets. These, at the top of the furnace, are introduced in such a way as to provide a constantly descending body without permitting escape of the gas, which passes off through its own discharge pipe or pipes, not shown. These features it has been deemed unnecessary to illustrate, as they are all understood in the art. At the lower end of the furnace, 85 the chemically-changed briquets are removed without permitting the escape of gas in a manner well known. Thus, we have a body or column of briquets constantly vertically descending, and traversing such body we 90 have an upward flow of gas, which, by reason of the vertical disposition or arrangement of the column becomes evenly and uniformly dispersed therethrough in a way to facilitate an efficient operation of the appliance.

It is, of course, necessary to heat such mixture to bring about the usual chemical action required, and this is done in a limited or circumscribed intermediate section 100 or zone only of the material. This result is desirably accomplished by a plurality of electric-arcs maintained in the usual way between electrodes outside of the passage but adjacent to the member 10. Consequently, in an outer annular heat chamber or compartment 13 surrounding the body 10 I provide such heating means, the outer wall of the chamber comprising an inner portion or lining 14 of carbon backed up with one 110

or more walls of heat-insulating bricks 15 and 16 and an outer metal-shell 17. The exact construction of this wall is of no importance except that it must be able to withstand or resist the high degree of heat employed and prevent escape or material loss of such heat.

As is clearly illustrated in Fig. 1, the outer surface of the member 10 is of octagonal shape and against its alternative flat surfaces at the central or intermediate section only of the furnace, the inner end of four electrodes 18, 18, bear so that they are in direct physical contact with the member 10 and hence readily transmit heat to it. Adjacent to such inner ends of these electrodes, and disposed at right angles thereto, are four other companion electrodes 19, 19, each of which is adapted to establish an arc between 20 itself and its companion electrode 18, all as is clearly shown. These electrodes extend substantially radially through the outer wall of the furnace and are suitably connected to an electrical circuit to maintain the electric arcs in a manner indicated. It will be perceived that these arcs and electrodes are all in the same horizontal plane and relatively close together, and since the arcs produce concentrated heat, we have the conduit or 25 passage 11 at an intermediate portion raised to a high degree of heat sufficient to carry out the desired chemical reaction.

The operation of the appliance takes place practically as follows:

30 The briquets travel down the conduit continuously in a solid body and the gas flows up through such body in a vertical direction without cessation and becomes evenly distributed through such body. At the zone 35 or section of the conduit heated by the arcs the temperature of the mixture is raised sufficiently so that the chemical change occurs, the column of material at this point being substantially uniformly heated throughout.

40 The gas in passing upwardly to the heat-zone through the briquets, which have already passed downwardly through such zone, is initially heated to a desirable temperature, and the briquets above the heat-zone descending to the latter are preliminarily heated by the upwardly flowing hot gas which has previously traversed the heat-zone, so that both of the ingredients, solid and gaseous, are first or preparatively raised 45 in temperature before they enter the hot section of the conduit, thus conserving heat, and tending to concentrate the latter at this particular portion of the appliance by reason of the two cool incoming ingredients 50 flowing in opposite directions thereto and tending to bank or hold back the heat in the hot-zone.

In Figs. 3 and 4 a somewhat different structure is employed, the only difference 55 being in the way that the heat is produced

and transmitted to the interior of the conduit or passage. In this case, none of the electrodes are in direct contact with the graphite or carbon body 10, but are close thereto, whereby the heat of the arcs is readily transmitted to the material to be treated. The appliance, as shown, has two pairs of electrodes 20, 20, and 21, 21, in the same plane, producing arcs adjacent to but on opposite sides of the briquet and gas containing member 10. Below these are two other pairs of electrodes 22, 22, and 23, 23, producing arcs on opposite sides of the body 10, but angularly offset with relation to the other arcs 90 degrees, so that four sides of 80 the member 10 are subjected to the heat of the four arcs, bringing about an adequate raising in temperature of the contents of the passage to produce the required chemical reaction.

85 It is not absolutely essential that the passage or flue through the furnace for the passage of the briquets and gas shall be vertical, but it may be more or less inclined, as illustrated in Fig. 5, and preferably in all 90 instances, the body of solid material is caused to pass through the conduit and heat-zone by reason of the action of gravity.

95 By those skilled in this art it will be appreciated that the desired advantages are secured by employing an apparatus of this character, that is to say, the gas and briquets are uniformly intermixed, and in such condition are evenly and adequately heated by electric arcs or otherwise, which heating 100 means in no way interposes obstacles to the proper passage of the material through the furnace. Also the two incoming ingredients are preliminarily heated by material, whether solid or gaseous, which has already 105 traversed the heat-zone, so that the discharging material is desirably cooled and the incoming material desirably initially heated.

I claim:

1. In a furnace of the character described, 110 the combination of a member having a conduit for the passage therethrough of the material to be treated, and means to heat the contents of said conduit located externally of said member, said member forming no 115 part of said heating means, substantially as described.

2. In a furnace of the character described, 120 the combination of a member having a conduit for the passage therethrough of the material to be treated, and electrical means to heat the contents of said conduit located externally of said member, said member forming no part of said electrical heating means, substantially as described.

3. In a furnace of the character described, 125 the combination of a member having a conduit for the passage therethrough of the material to be treated, and means to produce one or more electric-arcs to heat the con- 130

tents of said passage, said means being located externally of and forming no arc with said member, substantially as described.

4. In a furnace of the character described, 5 the combination of a member having a conduit for the passage therethrough of the material to be treated, and means to heat an intermediate portion only of the contents of said conduit, said means being located externally of said member, said member forming no part of said heating means, substantially as described.
5. In a furnace of the character described, 15 the combination of a member having a conduit for the passage therethrough of the material to be treated, and means located externally of said member to produce one or more electric-arcs to heat an intermediate portion only of the contents of said passage, 20 said member forming no part of said arc producing means, substantially as described.
6. In a furnace of the character described, 25 the combination of a member having a vertical conduit for the passing therethrough in opposite directions of the materials to be
- treated, and means located externally of said member to heat an intermediate portion only of the contents of said conduit, said member forming no part of said heat producing means, substantially as described. 30
7. In a furnace of the character described, the combination of a member having a vertical conduit for the passage therethrough of the material to be treated, and means to produce one or more electric-arcs located externally 35 of said member to heat an intermediate portion only of the contents of said conduit, said member forming no part of said arc producing means, substantially as described. 40
8. In a furnace of the character described, the combination of a member having a conduit for the passage therethrough of the material to be treated, and means to produce one or more electric-arcs located externally 45 of said member, including one or more electrodes in contact with said member, substantially as described.

MARK SHOELD.
